UNITED STATES PATENT OFFICE.

PHILIP J. ROBINSON, OF LEOMINSTER, MASSACHUSETTS.

HOLDER FOR TALKING-MACHINE RECORDS.

1,082,705.

Specification of Letters Patent.

Patented Dec. 30, 1913.

Application filed November 21, 1912. Serial No. 732,753.

To all whom it may concern:

Be it known that I, PHILIP J. ROBINSON, a citizen of the United States, residing at Leominster, in the county of Worcester and State of Massachusetts, have invented certain new and useful Improvements in Holders for Talking-Machine Records; and I do declare the following to be a full, clear, and exact description of the invention, such as will enable others skilled in the art to which it appertains to make and use the same.

This invention relates to improvements in holders for talking machine records.

One object of the invention is to provide 15 a holder of this character adapted to receive and securely hold the boxes containing the records and to be secured to a suitable supporting mechanism which may be inclosed in a cabinet or other receptacle.

20 One object is to provide a supporting mechanism for the record holders whereby a large number of records may be supported in a small space and in convenient position for use.

25 With these and other objects in view the invention consists of certain novel features of construction, and the combination and arrangement of parts as will be more fully described and claimed.

30 In the accompanying drawings: Figure 1 is a vertical sectional view through a record cabinet showing my improved record supporting mechanism and holders arranged therein; Fig. 2 is a central vertical sectional 35 view of the parts shown in Fig. 1; Fig. 3 is a horizontal sectional view thereof; Fig. 4 is an enlarged detail perspective view of one of the record holders removed from its supporting mechanism; Fig. 5 is a side view of

40 one of the holders and a portion of one of the bars of the supporting mechanism; Fig. 6 is a horizontal sectional view taken on the line 6—6 of Fig. 5; Fig. 7 is an enlarged vertical sectional view through a portion of 45 the top of the cabinet and through the upper ends of the inner and outer holder supporting cylinders mounted therein, showing more clearly the manner in which the ends of the cylinders are revolvably supported;

50 Fig. 8 is a front view of a modified form of holder supporting mechanism; Fig. 9 is an end view thereof; Fig. 10 is a detail perspective view of one of the supporting disks for the endless support or carrier shown in Figs. 55 8 and 9; Fig. 11 is an inner side view of a

portion of the endless carrier shown in Figs. 8 and 9.

Referring more particularly to the first seven figures of the drawings, 1 denotes a dust proof cabinet which may be of any suitable size and shape and which is here shown and is preferably octagonal. One side of the cabinet 1 is provided with a suitable door 2 through which access is had to the records contained therein. Revolvably mounted in the cabinet is an outer record supporting cylinder 3 and an inner record supporting cylinder 4. The cylinder 3 comprises upper and lower circular ends or heads 5 which are connected around their edges by a series of vertically disposed slats 6 the ends of which are secured to the edges of the heads 5 in any suitable manner. The slats 6 are spaced suitable distances apart and are designed to receive the holders 7 with which the record boxes are engaged and which are arranged one above the other on the slats as shown.

The inner cylinder 4 comprises heads or ends 8 which are connected around their edges by an annular series of slats 9 to which are also attached vertical series of holders 7. Access is had to the inner cylinder through a space or opening in one side of the outer cylinder, said space or opening being normally closed by double doors formed by hinged connecting two of the slats to the adjacent fixed slats with long leaf hinges 10 whereby said hinged slats and the holders thereon may be swung outwardly as clearly shown in dotted lines in Fig. 3 of the drawings.

The outer cylinder 3 is revolvably supported in the cabinet 1 by pivot screws 11 which are arranged through the center of the heads 5 of said cylinder and are secured in said heads by clamping nuts 12. The outer ends of the screws 11 are pointed and are revolvably engaged with tapered sockets 13 in bearing plates 14 which are secured to the inner sides of the top and bottom of the cabinet. In the inner ends of the screws 11 are also formed tapered sockets with which are engaged the pointed ends of pivot screws 15 which are secured in the center of the heads 8 of the inner cylinder 4 by jam nuts 16 as clearly indicated in Fig. 7 of the drawings. By thus mounting the inner and outer cylinders 3 and 4 it will be seen that they may be revolved independently of each

other thereby permitting any of the records in the holders thereon to be brought opposite to the openings or doors in the cabinet and also permitting any of the records on the inner cylinder to be brought opposite to the door opening in the outer cylinder.

Each of my improved holders 7 is formed from a single piece of wire, constructed as best seen in Figs. 4, 5, and 6. That is to say, the wire is bent at its center into an attaching or supporting eye 21 which stands in an upright plane and is adapted to be secured to the support or slat 6 by suitable means, and each stretch of the wire is then bent into an upper curved arm 17, the two arms complementing each other and together constituting an upper loop extending around about two-thirds of a circle and standing in a horizontal plane. From the outer ends of these arms the stretches of wire are carried downward into what might be called uprights 19 standing parallel with each other and preferably provided at about their mid-length with offsets or bends constituting thumb-notches 20. The stretches at the lower ends of said uprights are then carried inward and curved toward each other in two lower attaching arms 18 also occupying about two-thirds of a circle and standing in a horizontal plane so as to form a lower loop substantially like said upper loop, and where these arms 18 meet each other they are formed into a pair of overlapping attaching eyes 22 also standing in an upright or vertical plane directly under the eye 21 and adapted to be connected with the slat 6 in any manner. This much of the holder constitutes a pair of spring jaws whose inner edges are secured to the slat 6 at the points 21 and 22 and whose outer edges are the uprights 19 which may be sprung apart slightly to receive a record box as shown in Fig. 5, and then released so that the normal tendency of the wire forming the loops or eyes 21 and 22 will be to throw these jaws toward each other and grasp the box between them. The lower end of the holder or "foot" for supporting the box thus held between the jaws is by preference also made from the same piece of wire or rod, and this can conveniently be done by continuing the stretches below the eyes 22 in contact with each other so as to form a shank 23, and making a fork at the lower end of the shank which will underlie the space between the jaws occupied by the box. To make this fork or foot, the stretches are preferably bent at right angles to the lower end of the shank and carried outward away from each other in a horizontal line as at 24, and then bent forward at right angles and carried in parallelism with each other away from the support in fork-arms 25, which however should not be spaced apart as far as are the two jaws of the holder above. When now

said jaws are sprung apart to insert or remove a box, the fork-arms 25 may spring apart slightly but will not spring apart to such an extent as do the jaws because the two parts of the shank 23 are held together by the attaching device passing through the eyes 22 as will be understood.

In Figs. 8 and 9 of the drawings is shown a modified construction and arrangement of the record supporting mechanism which in this instance is in the form of an endless carrier comprising a series of horizontally disposed slats 26 which are spaced apart and are secured at their inner sides to endless chains or other flexible elements 27. The endless series of slats when thus connected are adapted to be engaged with upper and lower supporting disks or rollers 28 which are fixedly mounted on upper and lower supporting and operating shafts 29. The shafts 29 are revolvably mounted in bearing brackets 30 which may be secured to a wall or other support. The slats 26 and chains 27 are preferably covered by an endless apron 31 of cloth or other suitable fabric whereby an attractive background of any desired color may be provided for the records which are to be secured thereto and to the slats 26. Secured to each of the slats 26 and to the portion of the apron covering the latter are a series of record holders 32 which are constructed in the same manner as the holders 7 shown in the first form of the invention and which are secured to the slats 26 in the same manner except that the holders 32 are arranged in horizontal alinement on the slats as shown. As hereinbefore stated the holders 32 are constructed in exactly the same manner as the holders 7 and a further description of the holders 32 is not thought to be necessary.

Fixed on one end of the shafts 29 are belt pulleys 33 with which are engaged an endless operating belt 34, said belt being preferably passed one or more times around the pulleys whereby a firm engagement is provided between the belt and pulley and the pulleys 33 operatively connected to turn the shafts 29 in unison. On the upper shaft 29 at the end of the pulley thereon is fixed a large spur gear 35 with which is engaged a smaller gear or pinion 36 which is fixedly mounted on a short drive shaft 37 revolvably mounted in suitable brackets adjacent to this end of the carrier as shown. On the shaft 37 is fixed a grooved drive pulley 38 with which is engaged an endless operating belt 39 which is preferably passed one or more times around the pulley and which is similarly engaged with an idle pulley 40 mounted in a bracket 41 which is pivotally attached to the wall or other support and has connected to its outer end a weight 42 which pulls downwardly on the bracket 41, pulley 40 and the operating belt 39 whereby the

latter is kept stretched and sufficiently tight. By thus arranging the operating belt it will be seen that it is simply necessary for the operator to grasp one or the other stretches 5 of the belt and to pull upwardly or downwardly thereon, thus revolving the drive shaft 37, the movement of which will be imparted to the shafts 29 and carrier operating rollers through the gears 35 and 36 10 whereby the carrier is brought around in the proper direction for bringing the desired records within convenient reach of the operator. If desired the drive shaft 37 may be connected by a belt 43 with a drive pulley 15 44 on the shaft of an electric or other form of motor whereby power may be employed for operating the carrier when the latter is constructed on a very large scale for use in stores or distributing agencies. It will also 20 be understood that the carrier shown in Figs. 8 and 9 of the drawings may be inclosed in a suitable case or cabinet or otherwise covered to protect the records from dust. 25 From the foregoing description taken in connection with the accompanying drawings, the construction and operation of the invention will be readily understood without requiring a more extended explanation.

Various changes in the form, proportion 30 and the minor details of construction may be resorted to without departing from the principle or sacrificing any of the advantages of the invention as claimed.

Having thus described my invention, what 35 I claim is:

The herein described holder for talking machine records, the same being made of a single piece of wire bent at its center into a supporting eye standing in a vertical plane, 40 thence carried forward in a horizontal plane in two oppositely curved arms, thence carried downward in parallel uprights having thumb-notches at about their mid-length, thence carried horizontally inward 45 in two oppositely curved arms underlying those above mentioned, and the inner ends of these arms merging into a pair of attaching eyes standing in an upright plane; and a foot below the pair of jaws thus formed. 50

In testimony whereof I have hereunto set my hand in presence of two subscribing witnesses.

PHILIP J. ROBINSON.
